FASTENING INSERTING MACHINE

Filed Aug. 16, 1926

UNITED STATES PATENT OFFICE

GEORGE GODDU, OF WINCHESTER, MASSACHUSETTS, ASSIGNOR TO UNITED SHOE MANUFACTURING CORPORATION, OF PATERSON, NEW JERSEY, A CORPORATION OF NEW JERSEY

FASTENING-INSERTING MACHINE

Application filed August 16, 1926. Serial No. 129,425.

This invention relates to fastening-inserting machines, and in some aspects more particularly to the anchoring of staples in work into which they are driven, and is herein illustrated by reference to the use of staples for fastening uppers in lasted position in the manufacture of shoes. It will be recognized, however, that the invention, in its more general aspects, is not limited to the illustrated use, nor in fact to shoe manufacture, but has a comparatively wide range of utility.

In Letters Patent No. 1,742,500, granted upon an earlier application of mine on January 7, 1930, I disclosed and claimed novel means for anchoring staples by curving the legs of each staple laterally of its cross-bar, i. e., transversely of the plane determined by the legs and the cross-bar prior to such curvature of the legs, through force applied at the same side of the work from which the staple is driven, thus causing the legs to follow curved paths within the work such as to anchor them without the need of clinching them on any surface of the work. As applied, for example, to the fastening of the uppers to the insoles in the manufacture of shoes of that type in which the upper is fastened in lasted position to the plane bottom face of the insole, such means is especially useful, since the upper-fastening staples may be so applied as to avoid all danger of the presence of any sharp projections of metallic fastenings on the inner face of the insole.

The present invention affords still further insurance that a staple anchored, for example, as above described will be held securely in the work against strain tending to withdraw it, through the provision of means for effecting a relative deflection of the legs of the staple lengthwise of the cross-bar. As herein illustrated, both legs of the staple are deflected away from each other, or spread apart, as they are being driven and curved laterally of the cross-bar. Convenient means for accomplishing the object in view comprises a deflecting member or baffle plate for curving the legs during the staple-driving operation in the manner disclosed in the

above-mentioned Letters Patent, with guiding grooves so formed therein as to deflect the legs in the desired directions lengthwise of the cross-bar while they are being driven and curved. The staple is thus anchored in the work by the combined effect of the curvature of the legs laterally of the cross-bar and their deflection lengthwise of the cross-bar.

The invention further provides novel means for varying the curvature whereby fastenings are anchored in work. It is sometimes desirable, in operating upon shoes to fasten the upper to the insole, to curve the legs of upper-fastening staples differently in operating upon different portions of the same shoe, for example in the manufacture of a type of shoe in which the counter, at one side at least, extends forwardly into the shank portion of the shoe. Where there is thus an extra thickness of the upper materials the legs of the staple should be curved on a longer radius in order that they may secure an effective hold in the substance of the insole. As herein illustrated, a single deflecting member is provided for curving both legs, and associated with this member is mechanism for effecting a substantially instantaneous adjustment thereof to vary the curvature of the legs. For the purpose in view the adjusting means in the construction shown comprises a hand lever with adjustable stops for variably determining different positions of the lever corresponding to the desired degrees of curvature of the legs of staples in operating upon different portions of a shoe.

The invention in its different novel aspects will now be more particularly described by reference to the accompanying drawings and thereafter pointed out in the claims. The novel features are herein illustrated as applied to a type of machine such as described in the above-mentioned Letters Patent and in greater detail also in Letters Patent No. 1,742,499, granted upon another application of mine on January 7, 1930, although it is to be recognized that the invention is not thus limited in its applicability.

In the drawings,

Fig. 1 is a perspective view, on an enlarged scale, of a portion of the overlaying and fastening mechanism of a side-lasting machine such as shown in the above-mentioned Letters Patent, as modified for purposes of the present invention;

Fig. 2 is a cross-section, illustrating more fully the mechanism for varying the curvature of the staple legs;

Fig. 3 is a sectional view, illustrating how the staple is driven and how its legs are curved laterally of the cross-bar to anchor it in the shoe for fastening the upper materials in lasted position, the shoe and other parts being shown on an enlarged scale;

Fig. 4 is a view similar to Fig. 3, illustrating the wider curvature of the staple legs in fastening portions of the upper materials of greater thickness than those shown in Fig. 3;

Fig. 5 is a section on the line V—V of Fig. 3, illustrating how the deflecting member is detachably mounted;

Fig. 6 is a view, on an enlarged scale, of the deflecting member detached, showing the staple-guiding grooves whereby the staple legs are spread apart as they are being driven and curved;

Fig. 7 is a view illustrating how the legs of the staple diverge from each other after the staple has been driven; and

Fig. 8 is a sectional view showing a portion of a completed shoe having its upper secured to the insole in lasted position by staples anchored in the manner herein described.

Since the general organization of a machine of the type illustrated is fully shown and described in the prior Letters Patent, it is only necessary to refer herein to the construction and manner of operation of certain instrumentalities which are closely associated with the work upon which the machine operates. It will be understood that the shoe, in the hands of the operator, is presented in engagement with an edge gage 10 and a bottom rest 12 and is moved from one position to another for the lasting of different adjacent portions of a side of the shoe successively. In each lasting position of the shoe the upper materials, hereinafter frequently referred to inclusively as the upper, and including, for example, the upper leather *a* and the lining *b* (Fig. 3), are pulled by a gripper (not herein shown), and are then laid inwardly over the insole *c* by mechanism including a carrier 14 which is moved in a direction inclined to the plane of the insole, the carrier having thereon a staple-guiding throat or nozzle which, in the construction herein shown, comprises a pair of separate members 16 which serve as the opposite side portions of the nozzle and are arranged to engage the upper to lay it over the insole.

The staple *s* for fastening the upper to the insole is formed with straight legs and is driven from the nozzle by a driver 18 provided with a guiding rib extending downwardly between the lower opposed edges of the nozzle members 16, as illustrated in Fig. 2. Above the driver, in the construction herein shown, is a pawl 20 controlled by a spring plunger 22 and having a front end portion arranged to extend between the legs of the staple to assist in guiding them as they are being driven, the pawl being lifted by the driver near the end of the staple-driving operation. Mounted also on the carrier 14 is a deflecting member or baffle plate 24 the lower end of which occupies a position opposite to the end of the staple-guiding passage in the nozzle members 16 for engaging the legs of the staple at the same side of the work from which the staple is driven, i. e., without the presence of any portion of the work between the deflecting member and the staple nozzle, and thereby deflecting or curving different portions of the legs successively laterally of the cross-bar and both at the same side of the cross-bar, before the different respective portions enter the shoe. The baffle plate 24 is so arranged that it acts also in conjunction with the nozzle members 16 to lay the upper inwardly over the insole.

It will be understood that, as the staple is driven in a direction inclined to the bottom face of the insole, and, as herein illustrated, inwardly from the edge of the insole with its cross-bar substantially parallel to said edge, the legs are deflected progressively substantially throughout their length so that they enter the shoe in directions approximately perpendicular to the plane of the insole and then follow curved paths such as to anchor them in the body or intact substance of the insole with their ends directed reversely toward that surface of the work at which they entered. The legs may thus be curved in such degree as not to penetrate the inner face of the insole, and their ends may or may not emerge from the outer or bottom face of the insole, since if they do so emerge, they will be covered by the outsole; and there is, in any event, no danger that the ends of the legs will work up into the interior of the shoe. It will be further noted that, with the staple driven in a direction inwardly from the edge of the insole, as illustrated, the legs are curved outwardly toward the edge of the insole in a direction substantially opposite to that of the drive.

It will be evident that the degree of curvature of the legs of the staple will depend upon the distance between the end of the staple nozzle, comprising the members 16, and the opposite wall of the deflecting member 24. It will be further understood that the degree of curvature which it is desirable to impart to the staple legs, in order to anchor

the staple in the insole in the most effective manner, depends upon the thickness of the upper materials through which the staple must pass before entering the insole, and the thickness of the upper materials which are to be lasted in the manner illustrated may thus vary considerably at different portions of the same shoe, especially in a shoe of the type in which the counter, at one side at least, extends forwardly into the shank of the shoe. The invention accordingly provides convenient means for quickly changing the degree of curvature of the staple legs. As herein illustrated, the deflecting member 24 is mounted to turn about a pivot pin 26 held detachably in place by a plate 27 (Fig. 5), and is engaged near its upper end by an eccentric 28 formed on a rotary shaft 30 on the outer end of which is secured a short lever 32. The lever 32 carries a spring plunger 34 having an edge portion 36 arranged to engage a series of teeth or corrugations 38 formed on a plate 40 which is secured to the carrier 14, so that the lever is retained frictionally in any position to which it is moved in adjusting the eccentric 28. It will be understood that, in accordance with the position of the eccentric 28, the distance between the lower end of the deflecting member 24 and the staple nozzle will be varied. It will be observed that no means is provided for holding the deflecting member against the eccentric, since no such means is necessary, the deflecting member being forced against the eccentric by the pressure of the first staple upon its lower end in the driving operation and retained thereafter in that position by friction of the parts.

It will thus be seen that when it is desired to change the degree of curvature of the staple legs, all that the operator has to do is to manipulate the lever 32 with one hand while holding the shoe in the other hand, the lever being positioned near the staple nozzle and only a short distance above the shoe. There is further provided adjustable means for limiting the movement of the lever 32 in opposite directions, so that after determining how the staple should be curved for the best results on the line of work upon which the machine is to operate, the operator may be sure that by moving the lever as far as permitted in one direction or the other the deflecting member will be adjusted to produce exactly the curvature intended. For this purpose the plate 40 is provided with a segmental slot 42, and extending through this slot at opposite sides of the lever 32 are stop screws 44 the heads of which are arranged to engage one side of the plate 40 while the ends of the screws are threaded into nuts 46 arranged for clamping engagement with the opposite side of the plate. Either of the stop screws 44 may thus be set in any desired position along the slot 42 and secured in that posi-

tion to act as a limiting stop for the lever 32. By adjustment of one of the stop screws 44 the normal curvature of the staple legs may be determined, while adjustment of the other stop screw will serve to determine the curvature in operating on parts of the shoe where the upper materials are unusually thick, as illustrated in Fig. 4. That figure shows a portion of a shoe where, in addition to the upper leather *a* and the lining *b*, there is also a counter *d* and a canvas reinforcing piece *e* through which the staple must pass before entering the insole. 75

In the construction herein shown there is provision for further adjustment to determine the proper curvature of the staple legs, the nozzle or throat members 16 being so mounted as to be adjustable, each independently of the other, in directions parallel to the line of drive, or toward and from the deflecting member 24. By reference to Fig. 2, it will be seen that each of the members 16 is mounted on a guideway formed on the carrier 14, and each member is held in adjusted position by a clamping screw 48 extending 80 through a slot 50 (Fig. 1) in the member. It will be evident that adjustment of either of the members 16 will serve to vary the curvature of one of the legs of the staple without affecting that of the other leg. It is contemplated that proper adjustment of the members 16 will be made in setting up the machine, and thereafter there will be no need for readjustment of these members except to compensate for wear of the parts. In order 85 to facilitate precise adjustment of the members 16, adjusting screws 52 are provided engaging the rear end faces of the members, these screws being held in adjusted position 90 by nuts 54. 95

In order to increase the holding power of the legs of the staple, and thus to afford further insurance that the staple will not be loosened in the work by the strain thereon, the invention provides for effecting a relative deflection of the legs of the staple lengthwise of the cross-bar, as herein illustrated by engaging them also on the same side of the work from which they are driven. For this purpose, the deflecting member 24 is provided on its staple-engaging face opposite to the end of the staple nozzle with non-parallel guideways or grooves 56 (Fig. 6) which receive and guide the legs as they are being driven and curved, these grooves in the construction shown being so formed that each of the legs is deflected in an outward direction, the legs thus being spread apart as they are driven into the work. The shape of the staple after it has been driven is indicated by Fig. 7, in which a portion of the work is broken away to show one of the staple legs in full. While I believe it to be preferable thus to deflect both legs in such manner as to spread them apart, the invention is not limited to 100 105 110 115 120 125 130

this particular manner of treatment, since the objects of the invention would, in greater or less degree, be accomplished by deflecting one of the legs alone or by deflecting one or both legs in a different direction or directions from those illustrated. The extent of the deflection may also be varied as may be desirable by suitably forming the grooves 56.

In Fig. 8 is shown a portion of a completed 10 shoe of the type illustrated, with the outsole *f* secured to the insole *c* by through-and-through stitches *g*, the staples *s* remaining as permanent parts of the shoe. A shoe thus made is of superior quality, not only by reason of the fact that it has no metallic fastenings clinched on the inner face of the insole in the locations of the side-lasting tacks commonly used heretofore, or so disposed that there is danger that the ends or points of the 15 fastenings will work up into the interior of the shoe; but also for the reason that, with the upper fastened initially yet permanently to the insole, in its original lasted condition, by staples anchored as herein disclosed, insurance is afforded that the upper will hold 20 the shape imparted to it in the lasting operation until the outsole is applied and secured to the upper and the insole.

While the invention is illustrated and described with particular reference to the manufacture of shoes of that type in which an outsole is secured to an insole by through-and-through stitches, it is considered that in various aspects the invention may be utilized 30 advantageously in the manufacture of other types of shoes, as well as in the still broader relations hereinbefore mentioned; and the term "sole" is accordingly used in many of the claims in a comprehensive sense to include both the insole of certain types of shoes 35 and also that part which in shoes of other types may be the outsole or the only sole with which the shoe is provided.

The novel method of anchoring staples 40 herein disclosed and the novel product of the method are claimed in a divisional application, Serial No. 334,525, filed on January 23, 1929.

Having described the invention, what I 50 claim as new and desire to secure by Letters Patent of the United States is:—

1. In a machine of the class described, the combination with shoe-positioning means, of means for fastening the upper of a shoe to the sole, said fastening means comprising mechanism for driving a staple through the upper and into the sole, and mechanism automatically operative in the driving operation to curve the legs of the staple substantially 55 throughout their length laterally of the cross-bar of the staple, and also to effect a relative deflection of the legs lengthwise of the cross-bar, to anchor them in the sole.

2. In a machine of the class described, the 60 combination with shoe-positioning means, of

means for fastening the upper of a shoe to the sole, said fastening means comprising mechanism for driving a staple through the upper and into the sole, and mechanism for engaging the staple at the same side of the work as the driving mechanism to deflect the legs laterally of the cross-bar of the staple and also lengthwise of the cross-bar to anchor them in the sole. 70

3. In a machine of the class described, the combination with shoe-positioning means, of means for fastening the upper of a shoe to the sole, said fastening means comprising mechanism for driving a staple through the upper and into the sole, and mechanism for engaging the staple at the same side of the work as the driving mechanism to curve the legs substantially throughout their length laterally of the cross-bar of the staple, and also to spread them apart, to anchor them in the sole. 80

4. In a machine of the class described, the combination with shoe-positioning means, of means for fastening the upper of a shoe to the sole, said fastening means comprising mechanism for driving a staple through the upper and into the sole, and a deflector arranged to act on the legs of the staple as they are driven to bend different portions of them successively, before the different respective 90 portions enter the sole, in directions transverse to the cross-bar of the staple and both at the same side of the cross-bar, and also to effect a relative deflection of the legs lengthwise of the cross-bar, to anchor them in the sole. 95

5. In a machine of the class described, the combination with shoe positioning means, of means for fastening the upper of a shoe to the sole, said fastening means comprising mechanism for driving a staple in a direction inclined inwardly from the edge of the sole with the cross-bar extending substantially parallel to the edge of the sole, and a deflector arranged to engage the staple at the same side of the work as the driving mechanism to curve the legs outwardly toward the edge of the sole, and also to spread them apart, to anchor them in the sole. 105

6. A machine of the class described having, in combination, means for driving a staple, and deflecting means arranged to engage the staple at the same side of the work as the driving means to curve the legs in the driving operation laterally of the cross-bar of the staple, and also to effect a relative deflection of the legs lengthwise of the cross-bar, to anchor them in the work. 115

7. A machine of the class described having, in combination, means for driving a staple, and deflecting means arranged to engage the staple at the same side of the work as the driving means to curve the legs in the driving operation laterally of the cross-bar of the staple and both at the same side of the 125

130

cross-bar, said deflecting means having guideways therein arranged to effect also a relative deflection of the legs lengthwise of the cross-bar.

5 8. A machine of the class described having, in combination, means for driving a staple, and a deflector arranged to bend different portions of the legs of the staple successively, before the different respective portions enter the work, in directions laterally of the cross-bar of the staple, said deflector being formed also to spread the legs apart as they are being driven.

15 9. A machine of the class described having, in combination, means for driving a staple, a guide for the staple, and a deflector positioned opposite to the outlet end of said guide for engaging the staple at the same side of the work as the driving means to bend the 20 legs laterally of the cross-bar of the staple as they are being driven, said deflector having non-parallel grooves therein for guiding the legs of the staple and effecting also a relative deflection of the legs lengthwise of 25 the cross-bar.

30 10. A machine of the class described having, in combination, means for driving a staple, and deflecting means arranged to engage the staple at the same side of the work as the driving means to spread the legs of the staple apart as they are being driven into the work for anchoring them in the work.

35 11. In a machine of the class described, the combination with means for driving a staple, of deflecting means for engaging the legs of the staple at the same side of the work as the driving means and curving different portions of the legs successively before the different respective portions enter the work, 40 and mechanism for adjusting said deflecting means to vary simultaneously and in the same degree the curvatures to be imparted to both legs of the staple.

45 12. In a machine of the class described, the combination with means for driving staples, of deflecting means for engaging the legs of each staple at the same side of the work as the driving means and curving different portions of the legs successively before the different respective portions enter the work, 50 and mechanism arranged for substantially instantaneous adjustment by the operator into one or the other of different predetermined positions to determine variably for different staples the degree of curvature of the legs effected by said deflecting means.

55 13. In a machine of the class described, the combination with means for driving a staple, of deflecting means for engaging the legs of the staple at the same side of the work as the driving means and curving different portions of the legs successively before the different respective portions enter the work, and 60 rotatable eccentric mechanism for adjusting

said deflecting means to determine variably the curvature of the legs of the staple.

14. In a machine of the class described, the combination with means for driving a staple, of deflecting means for engaging the 70 legs of the staple at the same side of the work as the driving means and curving different portions of the legs successively before the different respective portions enter the work, and mechanism for adjusting said deflecting means to determine variably the curvature of the legs of the staple, comprising a member movable by the operator to different positions and an adjustable stop for variably limiting the movement of said member to determine the curvature of the legs.

75 15. In a machine of the class described, the combination with means for driving staples, of deflecting means for engaging the legs of each staple at the same side of the work as the driving means and curving different portions of the legs successively before the different respective portions enter the work, and mechanism for adjusting said deflecting means to determine variably for different staples the curvature of the legs, comprising a member movable by the operator in opposite directions and adjustable stops for variably limiting the opposite movements of 80 said member.

85 16. In a machine of the class described, the combination with means for driving a staple, of a deflecting member for engaging the legs of the staple at the same side of the work as the driving means and curving different portions of the legs successively before the different respective portions enter the work, an eccentric for adjusting said member to determine variably the curvature of the legs of the staple, and means enabling the operator to effect a substantially instantaneous adjustment of said eccentric into different predetermined positions.

90 17. In a machine of the class described, the combination with means for driving staples, of a deflecting member for engaging the legs of each staple at the same side of the work as the driving means and curving different portions of the legs successively before 105 the different respective portions enter the work, an eccentric for adjusting said member to determine variably for different staples the curvature of the legs, a member for turning said eccentric, and adjustable stops 110 for variably determining opposite limits of movement of said member.

115 18. In a machine of the class described, the combination with a staple nozzle and means for driving a staple from said nozzle, of a pivotally mounted deflecting member for engaging the legs of the staple opposite to the end of the staple nozzle to curve the legs as they enter the work, an eccentric for controlling said deflecting member to determine 120 125 130

variably the curvature of the staple legs, a hand lever for turning said eccentric, and means for variably limiting the movement of said hand lever.

19. In a machine of the class described, a staple nozzle, means for driving a staple from said nozzle, and a deflector opposite to the outlet end of said nozzle for engaging the legs of the staple before they enter the work and for curving them in the driving operation, said staple nozzle comprising staple-guiding means adjustable toward or from the deflector to determine variably the curvature of the legs of the staple.

20. In a machine of the class described, a staple nozzle, means for driving a staple from said nozzle, and a deflector opposite to the outlet end of said nozzle for engaging the legs of the staple before they enter the work and for curving them in the driving operation, said staple nozzle comprising different portions arranged to guide respectively the opposite legs of the staple and adjustable each relatively to the other toward or from the deflector.

21. In a machine of the class described, a staple nozzle, means for driving a staple from said nozzle, a deflector opposite to the outlet end of said nozzle for engaging the legs of the staple before they enter the work and for curving them in the driving operation, said staple nozzle comprising different portions arranged to guide respectively the opposite legs of the staple and adjustable each independently of the other toward or from the deflector, and a rotatable threaded member for effecting the adjustment of each of said portions of the nozzle independently.

22. In a machine of the class described, the combination with means for driving fastenings, of deflecting means arranged to engage each fastening at the same side of the work as the driving means and to curve different portions of the fastening successively in the driving operation before the different respective portions enter the work, and a rotatable eccentric member arranged to be manipulated by the operator at will for adjusting said deflecting means to determine variably the curvatures of different fastenings.

23. In a machine of the class described, the combination with means for driving fastenings, of deflecting means arranged to engage each fastening at the same side of the work as the driving means and to curve different portions of the fastening successively in the driving operation before the different respective portions enter the work, a member movable by the operator at will to different positions for adjusting said deflecting means to determine variably the curvatures of different fastenings, and means for determining the different positions of said member.

24. In a machine of the class described, the combination with means for driving fasten-

ings, of deflecting means arranged to engage each fastening at the same side of the work as the driving means and to curve different portions of the fastening successively in the driving operation before the different respective portions enter the work, a member movable in opposite directions for adjusting said deflecting means to determine variably the curvatures of different fastenings, and adjustable stops for variably limiting the opposite movements of said member.

In testimony whereof I have signed my name to this specification.

GEORGE GODDU.
